UNITED STATES PATENT OFFICE.

HECTOR PLASSCHAERT, OF WACHTEBEKE-LEZ-GAND, BELGIUM.

PRINTING MECHANISM FOR REGISTERING MACHINES.

Application filed June 1, 1921. Serial No. 474,255.

To all whom it may concern:

Be it known that I, HECTOR PLASSCHAERT, manufacturer, of Wachtebeke-lez-Gand, Belgium, have invented new and useful Improvements in Printing Mechanism for Registering Machines, of which the following is a specification.

In the Plasschaert system apparatus for registering the arrival of carrier pigeons which forms the object of the Belgian Patents Nos. 186,825—186,896—204,138—and 213,204, one of the particular features consists in the mechanism for printing the time on the paper band, by means of a roller 15 which presses the band against a plate.

As is well known, the use of a roller enables a very clear impression to be obtained, at high speed, by exerting on the paper band a pressure relatively very light for pressing 20 the band against the plate.

The object of the present invention is a new mechanism for operating the roller in question.

In the Plasschaert apparatus described in 25 the inventions cited above, the movement of the roller which produces the impression takes place under the action of a return spring acting through flexible connections on the ends of the shaft of the said roller, so 30 as to cause a sudden movement of the latter during the printing stroke. Each end of the shaft is guided by the groove in a support.

This groove is composed of a horizontal portion which is connected at its two ends 35 with a portion having the form of arc of a circle. The horizontal portion thus forms the chord of the curved portion and serves for guiding the roller during the printing stroke.

40 In order to produce an impression on the paper band, the ends of the roller shaft are first moved in the curved portion of the guiding grooves, by the action on the ends of the roller shaft of two hooked driving arms, 45 which are pivoted at the geometric center of the said curved portions.

When the ends of the roller shaft thus driven have traversed the curved guides and have arrived opposite the straight horizontal 50 guides; they are automatically released by the hooks and are then brought back suddenly by a return spring but follow the horizontal portions of the guiding grooves. These horizontal portions are parallel to the 55 plane of the plate so that the roller passes rapidly over the paper band placed above the

said plate and thus produces the desired impression.

In the new printing mechanism, the hooked driving arms used for bringing the 60 roller into the operating position have been done away with and replaced by a geared winch mechanism with automatic release secured by the special teeth in the said gears, the supports with straight and curved guiding grooves have also been done away with 65 and replaced by guiding supports with double straight grooves.

These changes enable the dimensions of the apparatus to be reduced both in width 70 and to a greater amount in height.

Moreover, in the former mechanism, the adjustment of the pressure exerted by the roller for printing on the paper band is effected by raising or lowering the plate to- 75 together with the clock movement which drives the hands of the dials which mark the time, whereas the roller guides remain fixed.

In the new mechanism, the adjustment is made in the opposite way, that is to say, the 80 plate and the clock movement remain fixed, while the roller shaft guides can be brought closer to or moved away from the plane of the plate.

Simply for demonstrative purposes, a 85 method of constructing the new printing mechanism is represented of the accompanying drawing, on which:

Fig. 1 is an elevation and

Fig. 2 is a plan view, from above, showing 90 the assembly, while

Figs. 3 to 6 are diagrams of the winch mechanism and the roller guiding runway for bringing the roller into the position for being automatically released and causing the 95 release.

These diagrams show the roller and its driving chain as well as the automatic return winch gearing in the different positions occupied up to the moment of release.

100 Figs. 7 to 10 are diagrams showing the different positions occupied by the single toothed gear which produces the intermittent rotation of the drum with compartments called the "ring" drum (for receiving the rings designating the pigeons). These positions correspond respectively to those of the winch mechanism shown in Figs. 3 to 6.

The diagrammatic mechanism shown in 110 Figs. 7 to 10 having been completely described in the former patents cited above in connection with the printing mechanism, it

will not be otherwise mentioned in the following and the description as well as the claims will be strictly limited to the particular features of the new mechanism for operating the printing roller.

The latter mechanism, diagrammed in Figs. 3 to 6, is constituted and operates as indicated hereafter.

The shaft 12 of the printing roller 13 pivots, at each of its ends, in a bearing 14 carried by a chain 15.

In the initial position shown in Fig. 3, the upper end of the chain is wound on the drum of a spring barrel 16, while its lower end is completely unwound from a drum 17. Between the two drums, the chains 15 pass around idler pulleys 18 placed at a level somewhat lower than the drum 16.

A gear 19 with interrupted teeth 20 is mounted on a shaft 21 which can be rotated by a crank not shown. This gear has an end tooth 22 larger than the others for engaging the end tooth of the interrupted teeth 23 of a gear 24 mounted on the shaft 25 of the counter drum 17.

The shaft 21 carries, in addition, at the end nearest the crank a gear 25 whose single tooth 26 engages the teeth of a gear 27 mounted on the shaft 28 of the "ring" drum 29. (Figs. 7, 8 and 9.)

Each tooth of the gear 27 corresponds with one of the compartments 30 of the "ring" drum; the gear 27 turns therefore through an angle corresponding to one of the compartments 30 when the crank operating the shaft 21 makes one revolution.

The crank turns the shaft 21 and the gear 19 in the direction indicated by the arrow 31, the said gear 19 in turn driving the gear 24 as shown in Figures 4 and 5, which causes the chains 15 to wind on the counter drum 17.

In the position shown in Figure 6, the disengagement of the teeth frees the gear 24, and the chain 15 is pulled back by the action of the antagonistic spring placed in the barrel 16 but not represented.

The said chain then unwinds from the counter drum 17 is wound again on the drum of the barrel 16 bringing the roller back to its initial position as shown in Figure 3.

During the movement of the chain winding onto the counter drum 17 the printing roller 13 is carried along by the said chain and moved longitudinally as shown in Figures 3 to 6.

During this movement of the roller, the bearings 14 which support its shaft encounter a runway 32 placed horizontally. The runway therefore makes a certain angle 60 with the upper length of chain which is inclined.

The passage of the bearing 14 on the upper surface of the above mentioned runway, causes a raising of the upper length of chain 65 as clearly shown in Fig. 5, it being noted

that the dotted line would represent the normal direction of the chain if the runway was not there. Moreover, the bearings exert pressure on the runway since the chain is tightened by the action of the spring in 70 the barrel 16.

When the bearing 14 reaches the end of the runway 32, it is released from the runway by the tension of the chain and takes the position shown in Fig. 6. At the same 75 time, the driving gear 19 releases the driven gear 24 as shown in the said Fig. 6, on account of its interrupted teeth.

The gear 24 being thus freed, the chain 15 comes back suddenly, on account of being 80 rewound on the drum of the spring drum 16, and the mechanism returns to the position indicated in Fig. 3.

During the sudden return of the chain, the bearings 14 of the roller 13 come back, guiding on the lower surface of the runway 32, and, during this return stroke, the said roller exerts a pressure on the paper band 33 so as to press it against the plate 34 (Fig. 1) and produce the impression.

So as to better insure the engagement of the bearing 14 successively on the two surfaces of the runway 32, the two ends of the runway are beveled at 35 and 36.

From the above, it results that the "ring" 95 drum advances one compartment for each impression produced by the roller.

In the practical construction of the mechanism as shown in Fig. 1, the diagrammatic runway 32 with two surfaces is supplemented by two superimposed guide grooves 37 and 38.

The driving mechanism for the paper band 33 and the arrangement of the inking ribbon being, in principle, identical with those described in the former inventions cited above, no special indication will be given concerning them.

It will be perceived, without other explanation, that the pressure exerted by the roller for pressing the paper band 33 against the plate 34 may be easily regulated by lowering or raising more or less the double groove for guiding the shaft of the said roller.

The device enabling the double guide grooves to be raised or lowered at will is not described or represented herein as any craftsman is capable of constructing immediately and easily such a device, which besides does not form a particular feature of the invention.

What I claim is,

1. Printing mechanism of the class described, comprising a drum, spring rotated in one direction, a counter drum, flexible elements connecting said drums, a roller carried by said flexible elements and movable therewith back and forth between the drums, a runway for the roller arranged at an angle 125 130

to said flexible elements to cause said roller to move on one side thereof as said roller travels from the drum to the counter drum and to move on the opposite side thereof as 5 said roller travels in the reverse direction, and a printing element, opposite the last named side of the runway and against which said roller imparts a printing impression as said roller travels from the counter drum to 10 the drum.

2. Printing mechanism of the class described, comprising a drum, spring rotated in one direction, a counter drum, flexible elements connecting said drums, a roller carried by said flexible elements and movable therewith back and forth between the drums, a runway for the roller arranged at an angle to said flexible elements to cause said roller to move on one side thereof as said roller 15 travels from the drum to the counter drum and to move on the opposite side thereof as said roller travels in the reverse direction, and a printing element, opposite the last named side of the runway and against which 20 said roller imparts a printing impression as said roller travels from the counter drum to the drum, and means to operate the counter drum.

3. Printing mechanism of the class described, comprising a drum, spring rotated in one direction, a counter drum, flexible elements connecting said drums, a roller carried by said flexible elements and movable therewith back and forth between the drums, 30 a runway for the roller arranged at an angle to said flexible elements to cause said

roller to move on one side thereof as said roller travels from the drum to the counter drum and to move on the opposite side thereof as said roller travels in the reverse direction, a printing element, opposite the last named side of the runway and against which 40 said roller imparts a printing impression as said roller travels from the counter drum to the drum, and means, including a shaft 45 geared to the counter drum to operate the counter drum.

4. Printing mechanism of the class described, comprising a drum, spring rotated in one direction, a counter drum, flexible elements connecting said drums, a roller carried by said flexible elements and movable therewith back and forth between the drums, a runway for the roller arranged at an angle to said flexible elements to cause said roller 50 to move on one side thereof as said roller travels from the drum to the counter drum and to move on the opposite side thereof as said roller travels in the reverse direction, a printing element, opposite the last named 55 side of the runway and against which said roller imparts a printing impression as said roller travels from the counter drum to the drum, and controlling means, including a driving shaft and interrupted gears connecting said shaft to the counter drum, to alternately operate and release the counter drum. 60

In witness whereof I affix my signature.
HECTOR PLASSCHAERT.
